UNITED STATES PATENT OFFICE.

WILLIAM M. SCOTT, OF TREDYFFRIN TOWNSHIP, CHESTER COUNTY, PENNSYLVANIA.

OPERATING MEANS FOR CIRCUIT-CONTROLLING MECHANISM.

Application filed December 16, 1926. Serial No. 155,219.

My invention relates to operating means for circuit-controlling mechanisms and more particularly to operating means for switches or circuit-breakers of the type which may be actuated by a plurality of sources of power, more particularly of the type which may either be actuated manually or controlled from a more or less remote point, by the application of power.

10 My invention resides in an operating means of the character above described, whose movement is modified, more particularly, retarded, when effected by one source of power, more particularly, by the means 15 controlled from a remote point.

Specifically, my invention resides in an operating means of the character mentioned, which, when actuated manually, opens or closes a switch or circuit breaker, and which, 20 when actuated by a remotely controlled means, more particularly, an electro-magnet, trips a switch or circuit breaker immediately or closes it after an interval.

25 My invention further resides in the features of novelty hereinafter described and claimed.

Fig. 1 is a side elevational view of a switch or circuit-breaker, embodying my invention.

Fig. 2 is a front elevational view of the 30 structure shown in Fig. 1.

Fig. 3 is a sectional view taken on line B—B of Fig. 1, of part of the electro-magnetic operating mechanism.

Fig. 4 is a fragmentary side elevation, and 35 on a larger scale of the retarding device and its operator shown in Figs. 1 and 2.

Fig. 5 is a fragmentary plan view of parts shown in Fig. 4.

Figs. 6 and 6^a are fragmentary sectional 40 views, with parts in elevation, taken on line 6—6 of Fig. 5.

Fig. 7 is a diagrammatic view, illustrating a possible circuit arrangement which may be employed.

45 Upon a base 1 of suitable insulating material, such as slate or marble, are secured the terminal blocks 2 and 3, with which electrical communication is afforded through the conducting studs 4. Adapted to bridge 50 and electrically connect contacts 2 and 3 is the movable contact member 5, preferably laminated. When so constructed, and particularly when heavy currents are carried thereby, the member 5 acts as a stiff spring 55 which is under compression when the switch or circuit breaker is in the closed-circuit

position. This member is fastened in any suitable manner to the arm 6 pivoted in the housing 7 at 8. The metallic shunt contact 9, and the carbon shunt contact 10 are also 60 carried by the pivoted arm and engage, respectively, the fixed, metallic contact 11 and the carbon contact 12. During the circuit-opening movement of member 5, the current is shunted through these contacts which open 65 in succession, the final arc taking place between the carbon contacts.

The actuating lever 13 pivoted to the housing 7 at 14, is provided at its inner end with a pin 15, which serves as a movable pivot for 70 the bifurcated link 16. The arm 17 is pivoted at one end, as at 18, to the housing 7 and at its other end is pivoted the link 16 as at 19.

The link 16 is provided with a surface 75 adapted to engage an extension of lever 13 to prevent the over-travel of the toggle comprising the links 13 and 16, the end pivots being 14 and 19, and the intermediate pivot 15. A second toggle, not completely shown, 80 is comprised of links 17 and 20, the end pivots being 18 and 19 and the intermediate pivot is 21. A spring 22 is connected at its one end to the pivoted arm 6 and its other end to the pivot 15, forming a connection 85 between toggle links 16 and 13. This spring is under tension when the switch is in the closed-circuit position, as shown in Fig. 1.

The switch or circuit breaker is maintained in that position by the gravity latch 90 or weighted dog member 23, which is pivoted at one end at 15 and at the other end engages the roller 24, pivoted at 25 to the housing 7. The latch member thus receives the thrust of spring 22 and prevents the collapse of the 95 toggles with consequent circuit rupture.

The housing member 26, fastened to the base member 1, by any suitable means and preferably made of a magnetizable material, receives the coil 27 in the annular groove 28 100 in its upper face, which, when energized, attracts the armature 29 from its biased upper position against the stop 30. This movement of the armature is transmitted to, and causes the counterclockwise rotation of, the 105 tripping arm 31, pivoted to the housing 7 at 25, by the connecting link 32. The offset extension 33 of the member 31 pushes the latch 23 from engagement with the roller 24, whereupon the tensioned spring 22 110 causes the collapse of the toggles described. The movable contact flies to the open circuit

position and the actuating arm 13 rotates counterclockwise from the position shown in Fig. 1.

The levers 34, pivoted at 35 to the housing member 26, are connected to the switch actuating lever 13 by the rod 36, which, at its upper end, is suitably fastened in the block 37 to the member 13 at 38, and at its lower end is likewise attached to a yoke member 39 through the end of which passes the pin 40. The handle 41 and the pin 40 are connected to each of the levers 34 so that upon actuation of the handle, movement is imparted to the levers 34 and thence to the switch actuating arm 13, through the pin 40, yoke 39, rod 36, block 37 and pin 38.

To close the switch manually, the handle 41 is grasped and the lever 34 moved in a clockwise direction to the position shown in Fig. 1. During the movement the lever 13 rotates in a clockwise direction, tensioning the spring 22 and, at the same time, moves the toggle members to the position shown in the same figure. The latch 23, under its own weight or by a biasing means not shown, engages the roller 24 as previously described and prevents the toggles from collapsing when the handle 41 is released. This operation is more fully described in my Patent 1,193,622 which utilizes similar structure. The switch or circuit breaker may also be closed by energization of the solenoid coil 42 disposed in the housing 26, which, when current is applied, attracts the core member 43 to an upper position. The movement of the core is transmitted to the switch-operating lever by the cross rod 44, which extends transversely through the guide slot of member 45, which is attached to the lower end of the housing 26. The rod is firmly secured to the core 43 by machine screws as indicated or in any suitable manner, and its ends are pivoted as at 47 in the depending links 48, which are, in turn, pivotally supported by the operating levers 34 at 49.

The core is movable in a cylinder 50, preferably of non-magnetic material such as brass, and is provided with an expanding ring 51, or other suitable packing means. During the downward movement of the core, the chamber formed above the top of the piston is in communication with the atmosphere not only through port 55 and apertures in guide member 61 but also through port 52, which extends longitudinally of the core member 43 having an outlet 52^a, at its lower end, and which is enlarged at its upper end to form a seat for the ball check-valve 53. The apertured plate 54, or any equivalent, prevents the ball from leaving the core plunger member during movement of the core, particularly in a downward direction, when the ball temporarily leaves its seat.

The space above the piston is also in com-

munication with the atmosphere through port 55, which extends to the outer surface of the housing 26 and is continued to valve-casing 56 by a connection plug 57, threaded into each of these members. Packing ring 58 is clamped between the housing 26 and the plug 57 in the manner shown in Figs. 6 and 6^a. The valve casing is provided with two valves, one of which, valve 59, may be opened or closed, and the other of which, valve 60, is normally always open, although the extent of the opening is variable at will. Each of these valves controls the passage of air between the port 52 and the atmosphere. The movable valve member 59 passes through, and is guided by, the apertured plug 61, threaded into the upper end of the member 56. It is biased to an open position by the spiral spring 62 which exerts an upward pressure on the levers 63, pivotally connected to the valve at 64 and to an extension of the valve casing at 65. The movement of the valve to the closed position is effected by the electro-magnet 66, whose pivoted armature 67 has an extension 68, which engages the prolongation of one of the levers 63. The armature may be biased to its unattracted position by the valve-opening spring 62. The core member 69 is threaded into the housing 26 and supports the coil of the electro-magnet.

The circuits, including the electro-magnets, are controlled by two switches, one of which is manually operated at a remote point and the other of which is automatically actuated by the movement of switching mechanism. The latter switch consists of a single, movable contact member, 70, which alternately engages the fixed contacts 74 and 75.

The movement of this switch is effected by the rod 71, connected at its upper end to the switch mechanism and at its lower end provided with a slot in which the pin 72 is free to slide. The horizontally angular arm 73 is rigidly attached to the cross rod 44 and transmits its movement to movable contact 70 through the pin 72 and the extremities of the slot of 71, as the cross rod approaches the limits of its travel. The relation of the parts is such that the arm 70 is in engagement with contact 74 when the rod is in the lower position, and in engagement with contact 75 when the rod is in the upper position.

Referring to Fig. 7, the terminals of the trip coil 27 are connected respectively to the fixed contact 75 of the automatically operated switch and to the fixed contact 76 of the remote control switch 77. The coils 66 and 42 are connected in series with each other and with the contact 74 of the automatic switch and contact 78 of the manually operable switch 77.

Operation.—Assuming the main contact member 5 to be in the closed circuit position,

the movable arm 70 will be in engagement with fixed contact 75. By moving the remote-control member 77 in a counter-clockwise direction to engage the fixed contact 76, the trip coil 27 is energized and the switch opens in the manner previously described. As the mechanism comprising the actuating arm 13, the operating lever 84 and associated elements, approach the limit of their movement during such circuit-opening operation, the pin 72 engages the bottom of the slot in the rod 71 and throws the movable contact 70 out of engagement with contact 75 and into engagement with contact 74, de-energizing the circuit of the tripping coil, though the manually operable contact 77 remains in contact with 76. The tripping arm 31 may also be actuated by means not shown, responsive to a condition of the circuit controlled by the contacts 2, 3, and 5.

The core member 43, being connected to the operating arm by the link 48, is positively impelled in a downward direction, and, since the space above the core plunger 25 is in communication with the atmosphere through the port 52, and also through port 55 communicating with the apertures in guide member 61, the retarding effect exerted on the movable switch mechanism during its switch-opening movement is a minimum.

The switch may also be opened by the direct manipulation of the trip arm 31, instead of by the energization of a trip coil. The switch may be closed manually in the manner previously described, and, since the chamber above the piston is in free communication with the atmosphere through both of the valve openings associated with port 55, such movement is unhampered by the presence of the passive core plunger of the electro-magnet 42. The movable contact member 70 is restored, during re-closure, to its original position in engagement with contact 75, so that opposite movement of same may subsequently be effected electromagnetically.

When the main contact 5 is in the open circuit position, the automatically operated contact 70 is in engagement with the fixed contact 74. By moving the remote control switch in a clockwise direction to engage contact 78, coil 42 is energized and, as previously described, moves the plunger 43 upwardly to close the switch. This upward movement is not free, however, as in the case when the switch is manually closed. The coil 66, being in circuit with coil 42, is energized simultaneously with it and attracts armature 67 to close the movable valve 59, so that the air trapped above the piston may escape only through the adjustably restricted opening regulated by the second valve 60. As the switch or circuit-breaker 60 mechanism approaches the fully closed-cir-

cuit position, the movable switch blade 70 is forced out of engagement with contact 74, breaking the circuit, and into contact with 75, so that the succeeding switch operation may be effected from the remote control 70 station.

The circuit condition of the main switch may be indicated at the remote control point by lamps or other suitable indicators 79 and 80, which are alternately energized as the main switch is opened and closed by the double throw switch 83, suitably connected to any moving part of the main switch mechanism, such as by a lever 84 having a slot which receives a reduced extension of the cross rod 44.

What I claim as my invention is:

1. The combination with circuit-controlling means, of operating means therefor adapted to be actuated by any one of a plurality of sources of power and means whereby the movement of said operating means is modified only when effected by one of said sources.

2. The combination with circuit-controlling means, of operating means therefor adapted to be actuated by any one of a plurality of sources of power and means whereby the movement of said operating means is retarded only when effected by one of said sources.

3. The combination with circuit-controlling means, of operating means therefor adapted to be actuated either manually or by other application of power, and means whereby the movement of said operating means is modified only when effected by application of other than manual power.

4. The combination with circuit-controlling means, of operating means therefor adapted to be actuated by any one of a plurality of sources of power and means whereby the movement of said operating means in one direction is modified when effected by certain of said sources.

5. The combination with circuit-controlling means, of operating means therefor adapted to be actuated by any one of a plurality of sources of power and means whereby the movement of said operating means in one direction is retarded only when effected by certain of said sources.

6. The combination with circuit-controlling means, of operating means therefor adapted to be actuated by either of two sources of power and means whereby the movement of said operating means in one direction is modified only when effected by one of said sources.

7. The combination with circuit-controlling means, of operating means therefor adapted to be actuated either manually or by other application of power, and means whereby the movement of said operating means in one direction is modified only

when effected by the application of other than manual power.

8. The combination with circuit-controlling means, of operating means therefor adapted to be actuated either manually or by other application of power, and means whereby the movement of said operating means is retarded only when effected by the application of other than manual power.

10. 9. The combination of circuit-controlling means, of operating means therefor adapted to be actuated by any one of a plurality of sources of power, and means whereby the movement of said second means is unrestrained in one direction and is restrained in another direction only when effected by certain of said sources.

10. The combination of circuit controlling means, of operating means therefor adapted to be actuated by either of two sources of power, and means whereby the movement of said second means is unrestrained on one direction and is restrained in another direction only when effected by one of said sources.

11. The combination of circuit controlling means, of operating means therefor adapted to be actuated either manually or by other application of power, and means whereby the movement of said second means is unrestrained in one direction and is restrained in another direction only when effected by the application of other than manual power.

12. The combination with circuit-controlling means, of current actuated operating means therefor, means for energizing said operating means, and current actuated means energized concurrently with said operating means to retard its movement.

13. The combination with circuit-controlling means of electro-magnetic operating means therefor, electro-magnetic means for controlling a fluid passage energized concurrently with said first electro-magnetic means to influence the movement of said operating means.

14. The combination with circuit-controlling means of electro-magnetic operating means therefor, electro-magnetic means energized concurrently with said first electro-magnetic means to retard the movement of said operating means.

15. The combination of circuit-controlling means, of operating means therefor adapted to be actuated either manually or electro-magnetically, and auxiliary electro-magnetic means energized when said operating means is electro-magnetically actuated to influence its movement.

16. The combination of circuit-controlling means, of operating means therefor adapted to be actuated either manually or electro-magnetically, and additional electro-magnetic means energized when said operating means is electro-magnetically actuated to retard its movement.

17. The combination with circuit controlling means, of electro-magnetic operating means therefor, and additional electro-magnetic operating means energized concurrently therewith for controlling a fluid vent and thereby affecting the rate of movement of said operating means.

18. The combination with circuit controlling mechanism, of operating means therefor adapted to be actuated either manually or electro-magnetically, and electro-magnetic means adapted to be energized only concurrently with the energization of said electro-magnetic operating means for restricting the escape of an elastic fluid opposing movement of said means, whereby retardation of said means in one direction is effected.

19. In an electro-magnetically operated circuit controller, manual and electro-magnetic operated mechanism therefor, auxiliary electro-magnetically operated means for controlling a valve regulating the degree of fluid resistance to the movement of said operating mechanism whereby the resistance is a maximum when said operating mechanism is electro-magnetically actuated.

20. In an electro-magnetically operated circuit controller, manual and electro-magnetic operating mechanism therefor, electro-magnetic operating means controlling fluid escape whereby resistance to movement of said operating mechanism in a given direction is varied within predetermined limits, said limits depending on the method of actuating said operating mechanism.

WILLIAM M. SCOTT.
